US0D1076833S

(12) **United States Design Patent** (10) **Patent No.:** **US D1,076,833 S**
(45) **Date of Patent:** **** May 27, 2025**

(54) **REMOTE CONTROL FOR FOOT STIMULATOR**

(71) Applicant: **HAIKOU LILI INVESTMENT CO., LTD.**, Haikou (CN)

(72) Inventor: **Junyuan Chen**, Haikou (CN)

(73) Assignee: **HAIKOU LILI INVESTMENT CO., LTD.**, Haikou (CN)

(**) Term: **15 Years**

(21) Appl. No.: **29/941,093**

(22) Filed: **May 8, 2024**

(30) **Foreign Application Priority Data**

Apr. 28, 2024 (CN) 202430247776.8

(51) **LOC (15) Cl.** **14-03**

(52) **U.S. Cl.** ..... **USPC** **D13/168**

(57) **CLAIM**

The ornamental design for a remote control for foot stimulator as shown and described.

DESCRIPTION

FIG. 1 is a perspective view of a remote control for foot stimulator showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.
